UNITED STATES PATENT OFFICE

2,472,026

ADJUSTABLE MOORING CABLE

Kenneth L. Peck, United States Navy, and Reinhold F. Balmer, United States Navy, Philadelphia, Pa.; said Balmer assignor to said Peck

Application July 25, 1946, Serial No. 686,098

4 Claims. (Cl. 24—115)

(Granted under the act of March 3, 1883, as amended April 30, 1928; 370 O. G. 757)

1

This invention relates to mooring devices and more particularly to improvements in adjustable mooring cable connections.

In the present invention we provide a mooring device by means of which a movable object may be easily moved to a supporting surface or another object. To accomplish this result we provide a toggle lever pivoted on a yoke with a link secured to the toggle lever adjacent the pivot and with the end of a cable connected to the link. The other end of the yoke is provided with a slot for the reception of a cable having spacers mounted thereon. These spacers are so constructed that when the cable is received in the slot of the yoke, the spacers arranged between the slot and the end of the cable regulate the effective length of the cable. The device to be moored is thus secured with some slack in the cable and movement of the toggle lever on its pivot takes up the remaining slack and locks the mooring in position.

An efficient mooring cable, while capable of use in many ways, is particularly desirable for use in connection with the operation of aircraft. While planes are awaiting operation or while being serviced and repaired, it is necessary to moor them against the forces of wind and weather and it is also necessary to moor planes when they are stored on the flight deck of a carrier. In normal times, this may be done by placing chocks in front of the wheels. In more severe weather, it has been the practice to moor them by means of cables or ropes fastened to the landing gear of the airplane at one end and to fittings on the deck of the ship at the opposite end. When an attempt is made to moor a plane with a piece of rope or cable, it is difficult to get mooring lines as taut as is desired by merely tying the cable in place. In the present invention we provide a mooring device which can be secured at one end to the aircraft and at the other end to the supporting deck or floor, most of the slack in the cable then taken up by means of the spacers provided at one end of the cable and the remaining slack then taken up by means of the toggle lever.

The mooring device also possesses the advantage that it can be as easily and quickly disconnected by swinging the toggle lever on its pivot which releases the tension in the cables providing sufficient slack to permit the end of the cable to be removed from the slot in the yoke and thus completely disconnect one end of the cable from the plane.

The above, and other objects of the invention, will be more fully apparent from the following specification and the accompanying drawing in

which the figure is an isometric view of the yoke and toggle lever showing the ends of cables connected thereto.

In the accompanying drawing the invention, as illustrated, consists of a cable 1 having a plurality of spacers 2 slidably mounted thereon. The spacers are in the form of sleeves or collars of a size to fit on the cable and are prevented from sliding off the end of the cable by any suitable means, such as ferrule 3. The end of the cable 1, having the spacers 2, is adapted to be received in a yoke 4 which, as shown, may be provided with a substantially U-shaped slot 5 at one end of any such size that the cable itself can slide through the slot, but which is too small for passage of the spacers 2. A toggle lever 6 is pivoted to the yoke at a point remote from the slot 5 and may be pivoted as illustrated at 9 at the other end of the yoke. Link 7 is in turn pivotally connected to the toggle lever as illustrated by the reference numeral 8 at a point spaced from the pivot. A cable fitting 10 carrying a cable 11 is secured to the other end of the link as indicated at 12. The other ends of the cables 1 and 11 may be provided with cable fittings 13 having eyes 14 to permit them to be secured to some suitable fastening means. The edges of the spacers 2 are preferably beveled as at 15 to permit easy separation.

The operation of the device will be apparent from the foregoing description. When the two cables 1 and 11 are used to moor a plane and to be secured to suitable supports on opposite sides of the plane, the fittings 13 are first secured and the cable 1 is passed through the yoke. When this cable has been fed through the yoke to an adjustment which will make it relatively tight, the cable is placed in the slot 5 with one of the spacers 2 at each side of the slot as indicated. The toggle lever 6 is then swung on its pivot from an open to a closed position. This moves the pivot of the link 8 around the pivot 9 of the toggle member and draws the end of the cable 11 toward the yoke thus taking up the remaining slack. The device may be as readily released by swinging the toggle lever 6 to an open position which produces enough slack in the mooring to permit the cable 1 to be readily removed from the slot 5. The invention has been illustrated with two separate cables 1 and 11 forming a part of the structure, but it is apparent that these two cables may in fact be the opposite ends of a single cable and the device may be used for many other purposes than the mooring of air ships to which the description has been particularly addressed.

From the foregoing, it will be observed that this

device greatly facilitates the mooring of aircraft by the quickness with which it can be engaged and disengaged, its selective length and positive means of tensioning. It is also light enough to be carried on board the plane.

While a particular embodiment of this invention has been illustrated and described herein, it is not intended that this invention be limited to such disclosure, and changes and modifications may be made and incorporated within the scope of the claims.

The invention described herein may be manufactured and used by or for the Government of the United States of America for governmental purposes without the payment of any royalties thereon or therefor.

We claim:

1. A mooring device comprising a pair of cable ends, spacers slidably mounted on one of the cable ends, a stop on the cable end beyond the spacers, a yoke comprising a pair of side members, an end member connecting the side members and having a slot therein to receive the said cable end between a pair of spacers, a toggle lever pivoted to the yoke adjacent the other end of the yoke, and means for connecting the second cable end to the toggle lever at a point spaced from its pivot.

2. A mooring device comprising a pair of cable ends, spacers arranged on one of the cable ends, a stop on the cable end beyond the spacers, a yoke comprising a pair of side members, an end member connecting the side members and having a U-shaped slot therein, the slot being of such size that the cable end can pass through it and between the side members of the yoke, but being smaller than the size of the spacers, a toggle lever pivoted to the yoke adjacent its other end, and means for connecting the second cable end to the lever at a point spaced from its pivot.

3. A mooring device comprising a pair of cable ends, spacers slidably mounted on one of the cable ends, a stop on the cable end beyond the spacers, a yoke comprising a pair of side members, an end member connecting the side members and having a U-shaped slot therein, the slot being of such size that the cable end can pass through it and between the side members of the yoke, but being

smaller than the size of the spacers, a toggle lever pivoted to the yoke adjacent its other end, and a link connected to the toggle lever at a point spaced from the pivot, the second cable end being connected to the link.

4. In a mooring device using cables, means for drawing two cable ends together comprising a series of spacers slidably mounted on one of the cable ends, a stop at the extremity of said first cable end beyond the spacers, a toggle lever linkage having a lever handle pivotally connected at a point spaced from its inner end to the second cable end, and a U-shaped yoke member having its open end pivotally connected to the inner end of the lever handle and having a slot in its closed end for receiving said first cable end between a pair of the spacers whereby said cable end may be inserted in the slot, taking up manually all of the slack between the cable ends by moving as many spacers as possible beyond the slot with the lever handle in the full extended position of the linkage, so that when the lever handle is operated the linkage will be shortened to tighten the cable ends.

Certificate of Correction

Patent No. 2,472,026.

May 31, 1949.

KENNETH L. PECK ET AL.

It is hereby certified that error appears in the printed specification of the above numbered patent requiring correction as follows:

Column 1, line 6, for the words "easily moved" read *easily moored*; and that the said Letters Patent should be read with this correction therein that the same may conform to the record of the case in the Patent Office.

Signed and sealed this 8th day of November, A. D. 1949.
